UNITED STATES PATENT OFFICE.

JOHN HENDERSON, OF CHICAGO, ILLINOIS.

FUSELAGE.

1,313,689.

Specification of Letters Patent.

Patented Aug. 19, 1919.

Application filed October 1, 1917. Serial No. 194,149.

To all whom it may concern:

Be it known that I, JOHN HENDERSON, a subject of the King of Great Britain, and a resident of Chicago, county of Cook, and 5 State of Illinois, have invented certain new and useful Improvements in Fuselages, of which the following is a specification.

The main object of this invention is to provide for aeroplanes and similar devices, 10 an improved frame structure having the desirable qualities of lightness, flexibility, and strength, and particularly capable of withstanding the torsional stresses and strains resulting from the engine and propeller 15 actions and unbalanced forces acting on the rudder, elevators, wings, and ailerons, when in flight. A further object of the invention is to make unnecessary the use of wires, brackets, turnbuckles, or other small fastenings in the frame structure which are likely 20 to become broken.

A specific embodiment of this invention is illustrated in the accompanying drawings, in which—

25 Figure 1 is a plan view of a monoplane showing the improved frame structure and engine support in dotted lines.

Fig. 2 is a fragmentary sectional detail 30 illustrating a suitable arrangement of the spiral and longitudinal frame members and also the method of connecting the frame members together at the front end of the fuselage.

Fig. 3 is a fragmentary detail showing a 35 suitable method of connecting the longitudinal frame members and the helical rib members of the frame.

Fig. 4 is a sectional detail of a modified form wherein the helical ribs are formed by 40 crimping the shell plating and applying the same in the form of a spiral strip with overlapping edges.

In the form shown, the fuselage comprises 45 a skeleton frame, having a torpedo shape and made up of helical frame members or ribs 1 and 2 suitably reinforced by longitudinal frame members 4. At the forward end of the aeroplane, the helical and longitudinal members are secured to an annular plate or 50 frame 3 to which the engine may be conveniently attached. The longitudinal members of the frame may be outside or inside of the helical rib members, this being merely a matter of design.

55 The spiral ribs preferably have a short pitch and may be few in number, two be-

ing shown in the drawings, each extending from end to end of the fuselage. These ribs may be of any suitable sectional form. In the form shown, they are made of flat strips 60 bent along longitudinal lines so as to have a T-bar cross section as shown in Fig. 3. At their forward ends, both sets of ribs are secured to an annular plate 3, and at their rear ends and also at each point of passing 65 of the longitudinal members 4, are welded or otherwise fastened to the spiral members. By welding together the longitudinal members and helical transverse members at their intersections, thereby forming an autogene- 70 ous union at each intersection, the entire framework becomes an integral structure, each portion reinforcing the adjacent portions in resisting and distributing the strains and stresses to which an aeroplane is frequently subjected. The supporting planes 5, elevators 6, and rudder 7, may be mounted on the fuselage in substantially the usual manner, and the framework of these devices may wherever practicable be provided with 80 spiral members as in the fuselage.

A cockpit, or space for the operator's seat, controlling devices, navigating instruments, and so forth, may be provided by inserting a suitable frame and cutting away or bending downward such of the spiral or longitudinal frame members as would otherwise extend across such space. The flexibility or rigidity of the frame is determined by the 85 number of spiral ribs and longitudinal mem- 90 bers and their cross sectional areas, and it will be readily seen that the use of spiral ribs for the transverse frame element provides great strength, with lightness, while at the same time having any desirable de- 95 gree of rigidity or flexibility.

The outer shell 9 may be fastened directly to the outer frame members or may be fastened to wooden battens 8 as shown in the drawings. The fuselage may be hollow and 100 substantially free from transverse struts, and therefore afford maximum storage space.

Although but one specific embodiment of this invention has been herein shown and described, it will be understood that details 105 of the construction shown may be altered or omitted without departing from the spirit of this invention as defined by the following claims.

I claim:

1. A fuselage for aeroplanes, comprising a 110 metal framework having longitudinal frame

members, and a continuous transverse member extending helically from end to end and the spirals thereof engaging each of said longitudinal members and being welded at the intersections, thereby forming an integral frame structure.

2. A fuselage for aeroplanes, comprising a metal framework having a plurality of spaced longitudinal frame members, and a

transverse spiral rib member, the spirals of which engage each of said longitudinal members, are continuous from end to end thereof and are autogeneously united thereto at the intersections to thereby form an integral frame structure.

Signed at Chicago this 28th day of September, 1917.

JOHN HENDERSON.
